DESIGN FOR A CLOTHES PEG

Douglas Nield, Dinas Powis, Wales

Application July 2, 1947, Serial No. 140,480
In Great Britain February 14, 1947

Term of patent 14 years

(Cl. D17—6)

To all whom it may concern:

Be it known that I, Douglas Nield, a subject of the King of Great Britain, residing at "Eastfield," Cardiff Road, Dinas Powis, in the county of Glamorgan, Wales, have invented a new, original, and ornamental Design for a Clothes Peg, of which the following is a specification, reference being had to the accompanying drawings, forming part thereof.

I claim:

The ornamental design for a clothes peg, as shown.

DOUGLAS NIELD.
